UNITED STATES PATENT OFFICE.

WILLIAM WALTER HARTMAN, OF LOS ANGELES, CALIFORNIA.

SWAB.

Application filed April 27, 1925. Serial No. 26,171.

This invention relates to swabs which may be inserted into oil or water wells to clean them, or to pump fluid out from them.

An object is to provide such a swab with a sealing cylinder or packer which retains flexibility radially but which strongly and effectively resists compression and distortion longitudinally, and is therefore exceptionally durable and powerful in practice.

10 Another object is to provide an effective metallic reinforcement for such sealing cylinders or packers, which reinforcement is stiff or rigid longitudinally and thereby imparts to the packers the above described qualities.

In swabs the resistance to longitudinal compression or distortion of the packer is of utmost importance because it prevents the packers under load from being compressed or mashed down into the casing joints of the well at the couplings, and being cut away at the bottom of the packer by the shearing action encountered when the swab is drawn up through the large number of such casing joints in a well. This is particularly important in my preferred types of packers which are characterized by having thick heavy walls that contact with the casing for a substantial distance along their 20 length to give good suction, only a moderate amount of clearance being allowed between the casing joint and the packer toward the bottom of the latter.

Even heretofore when using such thick walled packers without metallic reinforcement therein, no trouble was experienced by their being cut away or mutilated at the top, as these packers are usually sufficiently rounded at the top to prevent their upper 25 contour being in any way caught or damaged by irregularities of the casing, or at the casing joints. However, most such packers heretofore cut away very badly at the bottom because of the endwise compression of the load as above noted, and it is this bad cutting of the packers at the bottom which my invention effectively eliminates, or at least very greatly reduces, by preventing the longitudinal compression of the packer to which this cutting or shearing 30 at the bottom is due. Obviously this

reduces swabbing costs, and eliminates the delays and trouble of frequently replacing the packers.

My invention is broadly new in that I provide a simple rugged and easily assembled swab structure in which the body of the packers is very effectively held up against the load for the important purpose of protecting the bottom of the packers 40 against cutting as above noted.

In a structural way my invention broadly consists of a swab having a tubular stem, a valve for controlling the flow of fluid through such stem, a packer or packers on the stem, and a metallic supporting or reinforcing means, other than the stem, for effectively upholding the packers against endwise compression without danger of the reinforcement itself becoming caught in the 50 sections at the casing joints.

Except as specifically limited in the claims, the precise form and structure of this support or reinforcement, and its mode of association with the swab and packer, can of course be varied considerably without departing from the spirit of my invention, and such questions as to whether this support or reinforcement is completely or only 55 mostly concealed within the packer, or whether it is permanently molded into the packer or removable therefrom, do not affect the broader aspects of my invention even though some of the specific forms thereof illustrated in the drawings, and showing 60 the metallic support or reinforcement completely concealed and permanently molded within the packer, possess additional merit that will be apparent to those skilled in the art. This is particularly true of my wire 65 cage reinforcement which is simple and inexpensive to manufacture, and which possesses the various qualities and benefits of 70 this invention.

Other objects, advantages and features of 75 my invention may appear from the accompanying drawings, the subjoined detail description and the appended claims.

The accompanying drawing illustrates my 80 invention.

Figure 1 is a plan view of the swab, with 85 the stem shown in section.

Fig. 2 is a sectional view taken on line x^2 , Fig. 1, and with the casing also shown in section.

Fig. 3 is a side elevation of my swab, the casing being in section.

Fig. 4 is a fragmentary side elevation of my swab partly in section and with parts broken away to show the interior construction.

10 Fig. 5 illustrates three slightly modified forms of reinforcing.

Fig. 6 is a side view of another modified form of reinforcement.

15 Fig. 7 is a side view of my preferred form of wire reinforcing.

Fig. 8 is a section on line x^8 , Fig. 7.

The following is a detailed description of my preferred form of the invention.

20 The bottom member 1 of the string of tools commonly used in wells is threaded at its lower end to receive the threaded head or coupling member 2, which constitutes the upper extremity of my swab. A head 3 has a bore 4 extending longitudinally approximately the length thereof, and a pin 5 extends loosely through the end a and is threaded into the coupling 2, preferably permanently by a rivet c or other suitable expedient.

30 The member 5 is formed with an enlarged end 6 on which the head 3 rests, and about which said head swivels. A plurality of ports 7 extend through the wall of the head 3 into the bore 4.

35 A tubular stem 8 is threaded into the lower end of the bore 4 and depends from the head 3, any desired distance.

To the bottom of this stem a hollow tip or guide member 9 is threaded, which is 40 preferably tapered towards the lower end thereof, and a bore 10 extends through the lower end in which a ball 11 seats to form a downwardly closing valve.

A pin 12 extends through the tip 9 above 45 the ball 11 to limit the upward movement of said ball.

One or more sealing cylinders or packers 50 13 are positioned between the tip 9 and head 3, and surround the stem 8. Each of these packers have in conjunction with them a sleeve 14, which slides over the stem 8.

A downwardly facing shoulder 15 is 55 formed on the exterior surface and adjacent the lower end of the sleeve 14, and the outer surface of said sleeve approximately from the shoulder upwardly to the top may be fluted or corrugated as at 16, the purpose of which will be further described.

The packer 13 is formed of a more or less 60 yieldable or pliable material such as rubber, leather, fabric, etc., and surrounds the sleeve 14, the relation of the parts being preferably such that only a small space 18, or none at all, is provided between said packers and sleeve.

An annular seat 19 is formed in the bore of the packer 13, and the shoulder 15 of sleeve 14 rests firmly on this seat 19.

A metallic collar 20 is used below the lower end of packer 13. It embraces the stem 8 70 and is preferably provided with a recess 21 in which the said packer rests.

Flutings or corrugations 20' may be formed in the outer lower surface of the collars 20.

75 The lower end of sleeve 14, constituting a cylindrical skirt, rests against collar 20, and in assembling, a nut 22 threads on the stem 8 against the lowermost collar 20. The lowermost sleeve 14 engages the collar 20 next above it, and so on up until the uppermost 80 sleeve 14 engages the lower end of the head 3.

In this way when nut 22 is screwed onto the threaded stem 8, it butts all of the collars 20, and all the intervening sleeves or spacers 14, solidly against one another so as to make 85 a continuous and rigid arrangement with the nut 22 at one extremity and the head 3 at the other extremity. As this is done it is obvious that the packers 13 all become securely fastened and locked in place on the swab 90 longitudinally.

A reinforcement 23 is molded or otherwise introduced into packers 13, and in my preferred form this reinforcement consists of a cage formed of wire loops provided with 95 rounded upper looped ends as shown at 24.

Radially, this cage is preferably positioned in about the center of the packer 13, and should extend from below the top to a place in the vicinity of the bottom thereof. This provides a reinforced packer that is very stiff and strong vertically to resist compression under load, but is still expandable and contractible radially to compensate for the small differences in the size of various sections of the rough well casing as the swab is raised or lowered through the well. 100 105

The top rounded ends or shoulders 24, of cage 23, hold up the top of the packer without cutting or tearing out, and in this way the entire body of the packer is upheld, which in turn greatly reduces the cutting of the packer around the bottom by shearing of same under load at the casing joints as previously described. 110 115

Besides, when wire loops are used for the reinforcement, the fabric or rubber texture of the packer itself can be thoroughly joined or vulcanized all around the legs and beneath as well as above the upper supporting shoulder 24, which complete knitting or vulcanizing of the packer body around the reinforcement has further benefit in increasing the strength and durability of the packer. 120 Of course whether the cross section of the wire is round, flat, square or of other shape, or whether the loops at the top are rounded as shown or are of other suitable shape, is somewhat immaterial. 125

As shown in Figure 5, the reinforcement 130

23, instead of consisting of the looped wire cage above described, or of some modification of same, may consist of various other expedients of which the following are examples: As indicated in Figure 5 this reinforcement may consist of a plurality of very coarsely barbed posts 25 which may rise from a ring 26; or of posts 27 which may rise from a ring 28, and which are provided with shoulders or caps 29 at the top thereof; or of very coarsely threaded posts 30 which also may or may not rise from a ring 31 as desired. This reinforcement may also consist of a metallic cylinder 32, see Figure 6, preferably provided with large perforations 33, also with a substantial bead at the top, and also with longitudinal slits or slots 34 therein. It should be noticed that these modifications, like the wire cage, are all disposed lengthwise of the packer and approximately parallel to the axis of the tubular stem 8, which makes them very stiff and strong longitudinally. They also have their supporting shoulders or portions embedded or located within the packer below the upper end thereof, and this upper end is lapped or molded over the top of these supporting portions, or is otherwise supported by same, so that the friction and downward crushing force of the fluid load cannot appreciably compress the packer longitudinally or strip it down during operation. As previously stated this tends to prevent the bottom of the packer from being mashed out into the space between the casing sections and the coupling, and being cut away by the shearing action set up between the casing and the collar 20, which action would otherwise cut the packer at the bottom, just above collar 20, as the swab is pulled up through the well to lift the load.

It should also be noticed that by arranging the length of the reinforcing means 23, substantially parallel with the axis of stem 8, the risk of this metallic reinforcement, if unduly expanded radially under excessive load, itself becoming caught in the casing joints, is practically eliminated, and the importance of this is obvious.

By forming collar 20 in such manner that it has a projecting perimeter which embraces the bottom of the packer to a place above the bottom of the metallic reinforcement 23, additional rigidity is secured, as the bottom portion of the reinforcement and packer are further strengthened by this projecting perimeter of the cup or collar 20.

In addition to the modifications of the reinforcement 23 above described, other modifications may also be made without departing from this invention.

In operation the swab is lowered into the well casing α having the usual couplings γ between the joints, and as the swab passes down through the fluid, the liquid raises the

ball 11 off its seat, and passes upwardly through the tip 9, stem 8, head 3 and out of the ports 7, thereby becoming disposed above the swab in place of below it.

The packers or seals 13 are preferably of such diameter that they just pass down into the casing with practically no friction on the sides thereof.

Also I prefer that as nearly as practicable the packers should fill the space between the casing α and the stem or sleeve 14, only enough space being allowed to permit the packer to accommodate itself in passing through a tight joint of casing.

Of course this prevents the packer from collapsing radially under the action of the fluid as the swab passes down through the fluid into the well. In other words by using rugged packers of this character with thick substantial walls, I sacrifice the benefit of having collapsible packers to allow the fluid to rise around their outer surfaces on the down stroke, but the loss of this benefit is much more than offset by the very exceptional durability obtained, and by the very heavy loads that these thick walled reinforced packers can lift. Of course since practically all the fluid on the down stroke of my swab, passes up through my tubular stem 8, I prefer to make the bore of this stem quite large so that my swab still sinks very rapidly even though none of the fluid rises around the outside of the packer. Also by heavily rounding the thick top end of my packer, the same is spared, even in the absence of any metallic support 23, from any cutting or mutilation at the top, this being solely due to its thick rounded shape, and in this respect my invention is basically different from those other types of lightly constructed packers of distinctly flaring conical shape which have sharp upper edges at their top extremity to wipe tightly along the walls of the casing on the up stroke for more perfectly preventing leakage of the fluid. These lightly constructed packers with sharp delicate upper edges, must be externally embraced and protected by wires or bands extending beyond the top end there-

of for the purpose of protecting their thin upper edges from mutilation, and from being turned completely upside down by the weight of the load, and by the friction against the casing. I am aware that the external fluid pressure at the top rounded end of my heavy packers tends to radially compress or contract them so as to slightly separate them from the casing thereby permitting leakage, but by admitting this fluid pressure to the inside of my packer as well as to the outside, this pressure from within balances the pressure from without, so that the latter does not noticeably contract my packer radially or break its seal and I have

found that by thus allowing the pressures to

counterbalance one another in this way, the sealing function of my packers even with their rounded upper ends, is performed practically as well as with packers having a 5 relatively sharp upper extremity that scrapes or wipes tightly along the casing.

My flutings or grooves 16, in sleeve 14, assist in admitting the fluid pressure to the inside surface of the packers. Also shoulder 10 15, on sleeve 14, prevents upward displacement of the packer while sinking.

When the fluid that is being raised reaches the top of the well, it either spills out of the well or is otherwise suitably discharged 15 therefrom.

My invention relates to well swabs and well pumps as the construction of these is identical and the name interchangeable.

In practice I have used a single packer 20 on the stem 8 with very good results, but I have shown a multiplicity of these packers, sleeves and collars for the purpose of illustrating how effectively the structure lends itself to use of more than one packer 25 on the stem.

Attention is also called to my co-pending application filed May 16, 1925, Serial No. 30,727, it being understood that subject matter of invention shown but not claimed in 30 this application is reserved for and claimed in my co-pending application just referred to. Furthermore the structure shown in my said co-pending application is but another modification of the broader invention 35 which is shown and disclosed in this present application, and the broader claims herein are therefore intended to cover the same. Claims on the packer per se are in my said co-pending application Serial No. 30,727.

It is also understood that though swabs 40 are normally and usually employed to lift fluid in the manner described in this specification, nevertheless they are sometimes used in the reverse manner for forcing the liquid down through the well to clean out the perforations in the well casing below. In this case either the entire swab may be turned upside down, or else only the packers may be reversed with a suitable change in the 45 valve arrangement. However, my invention relates to swab devices used in this inverted manner as well as in their usual, normal, upright manner, and though the nomenclature 50 which I have employed in the specifications and claims of this application, is necessarily directed to the normal upright assembly 55 of the device for lifting fluid, nevertheless this nomenclature is intended to also cover and include the structure when reversed for 60 swabbing downward.

I claim:

1. A device for operating in well casings composed of sections of jointed pipe, said device comprising the combination of a tu- 65 bular stem, a valve permitting fluid to flow

one way through said stem but preventing fluid from flowing the other way through said stem, a thick-walled packer mounted on said stem, and longitudinally stiff metallic reinforcing means embedded in said packer 70 for holding same up against longitudinal pressure, said metallic reinforcing means being located entirely below and terminating short of the top end of said packer.

2. A device for operating in well casings 75 composed of sections of jointed pipe, said device comprising the combination of a tubular stem, a valve permitting fluid to flow one way through said stem but preventing fluid from flowing the other way through 80 said stem, a thick-walled packer mounted on said stem, and longitudinally stiff metallic reinforcing means embedded in said packer for holding same up against longitudinal pressure, said metallic reinforcing means 85 having a supporting shoulder also embedded in said packer adjacent to but below the top end thereof over which shoulder the top end of said packer is molded.

3. A device for operating in well casings 90 composed of sections of jointed pipe, said device comprising the combination of a tubular stem, a valve, a packer mounted on said stem, and metallic reinforcing means having a longitudinally rigid upright part 95 embedded in said packer for making said packer stiff longitudinally, the upright part of said metallic reinforcing means being substantially parallel to the axis of said stem and terminating below the top of said 100 packer.

4. A device for operating in well casings composed of sections of jointed pipe, said device comprising the combination of a tu- 105 bular stem, a valve, a packer mounted on said stem, and metallic reinforcing means for said packer forming an integral part of said packer, said metallic reinforcing means having a longitudinally rigid upright part substantially parallel to the axis of said 110 tubular stem, and also having a supporting shoulder in said packer adjacent to but below the top end of said packer over which shoulder the upper part of said packer is formed to firmly hold the packer up against 115 longitudinal pressure.

5. A device for operating in well casings composed of sections of jointed pipe, said device comprising the combination of a tu- 120 bular stem, a valve, a packer, longitudinally stiff metallic supporting means for upholding the upper part of said packer, said supporting means, in the normal assembly of said device, being disposed lengthwise in said packer and approximately parallel to the axis of said stem, said supporting means having a supporting shoulder located near 125 but below the upper extremity of said packer for upholding the upper part of said packer, said supporting means terminating below 130

the top edge of said packer and receiving its own support at a place nearer the bottom of the packer than the top of the packer.

6. A device for operating in well casings composed of sections of jointed pipe, said device comprising the combination of a tubular stem, a valve, a packer mounted on said stem, metallic reinforcing means for resisting endwise compression of said packer, said metallic reinforcing means having a longitudinally rigid upright part disposed substantially parallel to the axis of said stem and inserted between the internal and external surface of said packer and having a supporting portion engaging said packer below the top extremity of the packer, said top extremity of the packer lapping over said supporting portion to prevent the top edge of said packer from pulling down off said supporting portion during operation.

7. A device for operating in well casings composed of sections of jointed pipe, said device comprising the combination of a tubular stem, a valve, a packer mounted on said stem, said packer having its upper end unrestrained radially and its inner surface adapted to be exposed to fluid pressure, and longitudinally rigid metallic reinforcing means molded into said packer between the internal and external surfaces thereof and forming an integral part of said packer, said metallic reinforcing means having an erect part disposed lengthwise within the erect walls of said packer and extending substantially parallel to the axis of said stem, said erect part of said reinforcing means having a supporting portion in said packer below the top end thereof over which supporting portion the upper part of the packer is formed to hold said packer up against longitudinal pressure.

8. A device for operating in well casings composed of sections of jointed pipe, said

device comprising the combination of a tubular stem, a valve, a packer on said stem, and metallic reinforcing means embedded in said packer and comprising rising legs firmly joined together near their upper ends and below the top extremity of the packer to form a supporting shoulder for upholding the top part of the packer.

9. A device for operating in well casings composed of sections of jointed pipe, said device comprising the combination of a tubular stem, a valve, a packer mounted on said stem, said packer being adapted to have fluid under pressure admitted to the inside surface thereof, metallic reinforcing means for resisting endwise compression of said packer, said reinforcing means comprising wire looped up and down in an approximately circular path around said packer, said reinforcing means being embedded and practically concealed within said packer, and the upper looped shoulder of said reinforcing means being located below the top of the packer which is supported thereby.

10. A device for operating in well casings composed of sections of jointed pipe, said device comprising the combination of a head, a stem depending therefrom, a valve, a packer mounted on said stem and having an upwardly facing seat, a metallic collar supporting said packer from below, a sleeve within said packer, a downwardly facing shoulder on said sleeve located above and engaging the said seat on said packer, said sleeve having a cylindrical skirt depending therefrom below said shoulder and adapted to intervene between the packer and the stem, and means for securing said packer, collar and sleeve to the stem.

In testimony whereof, I have hereunto set my hand at Los Angeles, California, this 21st day of April, 1925.

WILLIAM WALTER HARTMAN.
